UNITED STATES PATENT OFFICE.

CHARLES D. MOSHER, OF NEW YORK, N. Y.

FURNACE.

1,410,708.

Specification of Letters Patent. Patented Mar. 28, 1922.

Application filed October 20, 1919, Serial No. 332,033. Renewed July 12, 1921. Serial No. 484,193.

To all whom it may concern:

Be it known that I, CHARLES D. MOSHER, a citizen of the United States, residing at New York city, in the county of New York and State of New York, have invented certain new and useful Improvements in Furnaces, of which the following is a specification, reference being had therein to the accompanying drawing.

10 My invention relates to improvements in supplementary combustion chambers and more particularly has reference to a conical form of combustion chamber adapted for attachment to a steam boiler outfit such as a 15 Scotch boiler, and may be used in addition to the usual coal burning furnaces.

Referring to the accompanying drawings, I have illustrated in Fig. 1 in front elevation a suitable form of Scotch boiler and furnace showing an application of my invention. Fig. 2 is a longitudinal vertical sectional elevation of the same. Fig. 3 is an enlarged longitudinal cross-sectional view on the line 3-3 of Fig. 1 illustrating the 25 conical combustion chamber adapted for burning oil, gas or other combustible. Fig. 4 is a view looking from left to right at the perforated damper plates hereinafter more fully described, and Fig. 5 is a plan view 30 looking down upon one of the fire brick segments of the conical chamber.

Referring now more particularly to Figs. 1 and 2, 6 indicates the outer walls of the boiler and furnace, and 7 the usual boiler 35 tubes thereof, 8 indicating the air heating tubes within the flue 9 of the conventional form of Scotch boiler. 10 indicates the supplementary conical combustion chamber shown to better advantage in Fig. 3.

40 Referring now more particularly to Figs. 3 to 5 inclusive, it will be observed that eight or any other convenient number of segments of fire brick or other suitable material, indicated by the reference character 11 may 45 be joined together forming a conical structure adapted to be retained by the corrugated band 12 which may be bolted together in sections as indicated at 13, the corrugations or buckling such as 14 being intended to contribute resiliency, or yielding to accommodate expansion, etc. This band may be secured adjacent the larger periphery of the conical combustion chamber as indicated at 15 in Fig. 3. The smaller periphery of said 55 conical chamber may also be secured by a suitable corrugated band such as 16. 17 in-

dicates the holes through the various sections of the fire brick or other refractory material which holes are preferably substantially rectangular in the form of elongated 60 slots as shown to better advantage in Fig. 4 upon the outside, and are preferably formed as round holes upon the inside as indicated at 18 in Fig. 3.

19 indicates curved plates also perforated 65 with elongated slots 20 adapted to register with elongated slots 17 upon the outside of the fire brick sections and these curved plates are preferably in the form of conical rings adapted to fit over the outside of the fire 70 brick sections as shown in Fig. 3 being separated and guided in the bands 21, so that the said conical rings or dampers being provided with a suitable rack 22 may be rotated by pinions such as 23-23'-23'' which may 75 be operated by a suitable tool such as the crank handle 24.

The burner for the combustible material is indicated by reference character 25 and so mounted as to deliver the charge of fuel 80 through the cap 26 which may be secured by any suitable means such as bolts 27 to the flanged rings 28 secured by the angle rings 29 to the front wall 30 of the chamber.

Referring now more particularly to Fig. 2, it will be seen that the air passing through the heating tubes 8 to the chamber 31 enters the chamber 32 where it is drawn or forced by a blower or other suitable means through the elongated slots 20 of the damper plates 90 and through the elongated slots 17 of the conical fire brick structure into the combustion chamber 10 where it is met by the in-rushing spray of fuel 33 and is consumed. By providing separate dampers at different 95 points along the longitude of the conical chamber, it will be readily appreciated that the mixture of fuel and air may be controlled at said points thereby providing for a wide range of adjustment for the mixture of the 100 fuel and insuring a proper and complete, as well as uniform distribution and combustion of the fuel as it passes through the furnace beneath the boiler tubes.

34 indicates a suitable hole or port cut 105 through the wall of the chamber 26, and 35 indicates a suitable transparent cover pivotally hinged beneath the screw 36 adapted to close said hole but through which the interior of the chamber 26 may be observed, 110 which also provides an opening for igniting the fuel when starting up. The perforated

bricks eventually become heated to a high temperature causing the jets of air in passing through them to be highly heated when ignition continues as long as fuel and air is supplied in proper amounts.

Of course it will be understood that various modifications may be made in the construction and arrangement of parts without departing from the spirit of the invention.

10 I claim:

1. In a combustion chamber of the class described, a conical chamber of incombustible material with air openings and a damper adjacent the exterior surface thereof for controlling the mixture of air and fuel therein, said openings arranged radially around a burner or source of fuel supply for jets of air to enter the conical chamber in approximately the opposite direction of the incoming fuel with a projection between the circular rows of holes to prevent or baffle the fuel from entering said air openings.
2. In a combustion chamber of the class described, a conical chamber of incombustible material, a burner adapted to supply fuel in cone-like formation, means for supplying tangential air jets around said burner said air jets being adapted to enter the conical chamber in approximately the opposite direction to the incoming fuel.
3. In a combustion chamber of the class described, a conical chamber of incombustible material, a burner for supplying fuel in

cone-like formation, openings around said burner for admitting air tangentially, said air openings through said conical chamber and pointing approximately in a direction opposite to the incoming whirling fuel, and a ledge between the circular rows of air openings forming grooves around the interior of the conical chamber, said air openings at the apex of said grooves, and the ledge at the base of said grooves forming a baffle to deflect the current of fuel from entering the said air openings.

4. In a combustion chamber of the class described, sections of incombustible material forming a conical chamber, and a damper adjacent the side thereof for controlling the fuel mixture, said damper being adapted to be controlled in sections.

5. In a combustion chamber of the class described, sections of incombustible material forming a conical chamber, and a damper adjacent the side thereof for controlling the fuel mixture, said sections having perforations extending radially therethrough, said perforations substantially rectangular at the outer surface and substantially circular at the inner surface.

In testimony whereof I hereunto affix my signature in the presence of two witnesses.

CHARLES D. MOSHER.

Witnesses:

DAVID H. DOUGLAS,
ANNA F. DUFFY.
